Inventor:
John Eaton,
by *Alfred S. Davis*
His Attorney.

UNITED STATES PATENT OFFICE.

JOHN EATON, OF SCHENECTADY, NEW YORK, ASSIGNOR TO GENERAL ELECTRIC COMPANY, A CORPORATION OF NEW YORK.

ELECTROMAGNETIC SWITCH.

1,334,144.

Specification of Letters Patent. Patented Mar. 16, 1920.

Application filed October 7, 1918. Serial No. 257,098.

To all whom it may concern:

Be it known that I, JOHN EATON, a subject of the King of Great Britain, residing at Schenectady, county of Schenectady, State of New York, have invented certain new and useful Improvements in Electromagnetic Switches, of which the following is a specification.

My invention relates to improvements in electromagnetic switches intended principally for use on alternating current circuits although not necessarily limited to this application.

As is well known, the armature or core of an electromagnetic switch tends to chatter against the stationary member when used on an alternating current circuit due to the alternations. This chattering is decidedly objectionable and various means have been provided for overcoming the difficulty. It has been found that if the moving part engages the stationary part so that it bears uniformly over the surface the chattering will be greatly reduced, if not entirely done away with. Where the parts are rigidly mounted, however, such a contact can only be obtained by very accurate work which involves expert hand workmanship the cost of which is very excessive. It has been found that substantially the same result may be obtained, however, by leaving the parts free to aline and adjust themselves to each other, and it is the object of my invention to provide a simple and effective arrangement whereby such alinement may be obtained. My invention will be understood from the following description taken in connection with the accompanying drawing in which I have shown my invention embodied in concrete form for purposes of illustration.

In the drawing Figure 1 is a side elevation of a magnetic switch embodying my invention; Fig. 2 is a side view of the armature and Fig. 3 is a sectional view of the armature mounted on the switch arm, taken on the line 3-3 of Fig. 2.

Referring to the drawings, 1 represents the insulating base upon which the switch parts are mounted. These switch parts consist of an electromagnet composed of a winding 2 mounted upon one leg of the U-shaped laminated core 3, provided with an air gap 4, and a switch arm 5, pivoted at 6. The arm 5 operates a contact member 7 which co-operates with a stationary contact

8 mounted on the base. The contact member is mounted on a shaft which extends laterally from the switch arm, and the contact portion 9 is yieldingly mounted so as to make a wiping contact with the stationary 60 contact 8 by means of a spring 10.

In accordance with my invention the armature, which is laminated, is mounted on a pin 15 which is secured at its ends in the switch arm 5, the hole for the pin being 65 the size of the pin for a very short distance at 16, and being enlarged at 17 and 18 so as to provide considerable clearance. The bearing at 16 is very short so that the armature may rock on the pin at the bearing in all 70 directions. This pin is preferably at the upper end of the armature. At the other end I preferably provide a pin 14 extending into a larger opening in the armature. The hole for the pin 14 provides clearance all 75 the way around so that normally the pin does not have a bearing in the armature. This pin, therefore, merely acts to limit the movement of the armature with reference to the arm 5.

By this arrangement it will be seen that when the winding 2 is energized the armature will be drawn up against the pole faces 12 and 13 and the armature, being loosely mounted, is free to aline itself so as to make 85 a uniform engagement with the two pole faces. The arrangement is exceedingly simple and involves no accurate fitting or surfacing.

While I have described my invention as 90 embodied in concrete form in accordance with the provisions of the patent statutes, it should be understood that I do not limit my invention thereto, since various modifications thereof will suggest themselves to those 95 skilled in the art without departing from the spirit of my invention the scope of which is set forth in the annexed claims.

What I claim as new and desire to secure by Letters Patent of the United States, is:— 100

1. An electromagnetic switch comprising an electromagnet and a pivoted switch arm, an armature therefor, and a bearing pin secured to the switch arm and passing freely through an opening in the armature, said 105 opening being reduced midway thereof to form a short bearing for the armature upon which the latter may rock.

2. An electromagnetic switch comprising an electromagnet and a pivoted switch arm, 110

- an armature therefor, a bearing pin secured to the switch arm and passing freely through one end of the armature but having a short supporting bearing thereon midway
- 5 on the armature upon which the latter may rock and a pin entering the other end of the armature but out of contact therewith when the armature engages the electromagnet.
3. An electromagnetic switch comprising
- 10 an electromagnet and a pivoted switch arm, an armature therefor, a bearing pin secured to the switch arm and passing freely through

a similarly shaped opening in the upper end of the armature said opening being reduced midway thereof to form a short bearing for 15 the armature upon which the latter may rock, and a pin entering the lower end of the armature but out of contact therewith when the armature engages the electromagnet.

In witness whereof I have hereunto set my hand this 3rd day of October, 1918.

JOHN EATON.
